MORRIS J. WHEELER AND FRANK B. FOSTER, OF PETERBORO, NEW HAMPSHIRE.

BASKET.

1,090,000.

Specification of Letters Patent. Patented Mar. 10, 1914.

Application filed July 26, 1913. Serial No. 781,376.

To all whom it may concern:

Be it known that we, MORRIS J. WHEELER and FRANK B. FOSTER, citizens of the United States, and residents of Peterboro, in the 5 county of Hillsboro and State of New Hampshire, have invented a new and Improved Basket, of which the following is a full, clear, and exact description.

Our invention relates more particularly to 10 a fruit or vegetable basket, and it is a design of the invention to provide a basket by which the fruit or vegetables may be handled and dumped from the basket without injury and with convenience.

15 The invention will be particularly explained in the specific description following.

Reference is to be had to the accompanying drawings forming a part of this specification, in which similar characters of reference 20 indicate corresponding parts in all the views.

Figure 1 is a perspective view of a basket embodying our invention; Fig. 2 is a sectional elevation with the basket sections in 25 the open position; Fig. 3 is a plan view of the fastening means for the basket sections, the top plate being removed; and Fig. 4 is a cross section of said fastening means on the line 4—4 of Fig. 3.

30 Our improved basket is composed of two sections formed of splints or other suitable material, the basket being divided vertically, and the sections being hinged at the upper edges, the construction being particularly 35 adapted to baskets formed of splints or like elements. The two similar sections 10 are curved transversely and at the upper ends the sections are hinged adjacent to their opposed edges by means of hinge members suit-

40 ably riveted to the respective sections and pivotally connected by hinge pins or rivets 12.

45 The pivots 12 serve also to secure the bail or handle 13. To the bottom of the basket fastening means are secured, the members 14, 15, being secured to the bottoms of the respective sections by bolts or equivalent means. One member of the fastener has a pivoted latch 18, the hooked end of which is adapted to engage a stud or like member 19 on the companion section. The latch is 50 pressed by a suitable spring 20, and a catch 21 on the opposite section is under the influence of a suitable spring 22 and has secured thereto in any suitable manner a wire 55 or string 23 for pulling the said catch. The latch pull includes a flexible element 24 in

the form of strap or band material, which extends vertically along one of the basket sections and is provided with a finger ring 25 near the upper end, whereby the latch 60 pull may be caused to disengage the catch 21 and release the latch 18, for permitting the basket sections to swing on their hinge pivots 12.

In the illustrated form each section 14, 65 15, of the latch includes top and bottom plates 26, 27 with spacing or filling elements 28 therebetween, which may be riveted, as at 29. The catch 21 is mounted to move longitudinally in response to a pull on the flexible 70 actuating elements 23, 24, to draw the said catch outwardly away from the latch 18. Upon the release of the flexible actuating elements, the spring 22 will force the catch 75 inwardly, in position at the back of the latch 18, preventing movement of the latter. When the latch 18 is released, the basket sections may be readily swung apart to dump the contents of the basket. Each basket section 10 comprises longitudinal 80 splints 30 and transverse splints 31 woven with the longitudinal splints, the said transverse splints being returned around the longitudinal splints at the opposed edges of the basket sections. 85

By the described construction the operator, while holding the basket by its handle 13, may conveniently exert a releasing pull on the latch 21, by placing a finger in the ring 25, and at the same time through the 90 medium of said ring, the basket section on which the ring is carried may be given a lateral pull relatively to the opposed section, to swing the sections apart.

Having thus described our invention, we 95 claim as new, and desire to secure by Letters Patent:

1. A basket, divided vertically forming two sections, hinges at the upper end of the basket pivotally uniting the said sections, a 100 handle pivotally secured by the hinge members to have a common center of movement with the basket sections, latching means on the bottom of the basket and comprising mating sections, the one having a latch and 105 other catch means for said latch, a flexible pulling element connected with the latch and extending upwardly to near the top of the basket, the latter having guiding means for said pulling elements, and a finger-hold 110 at the upper end of said pulling element, the said finger-hold constituting a means also to

swing the section carrying the same relatively to the other section.

2. A basket, comprising two similar sections having opposed open sides, each section being formed of longitudinal and transverse woven elements, the transverse elements being returned around the vertical elements at the opposed edges of the section, hinges uniting the sections at their upper edges, a handle pivotally held by the said hinges, latching means on the bottom of the basket comprising mating sections, a flexible latch-releasing means carried by one basket

section and extending through the transverse woven elements thereof, and a finger-hold secured to the upper end of the said flexible latch-releasing means. 15

In testimony whereof we have signed our names to this specification in the presence of two subscribing witnesses.

MORRIS J. WHEELER.
FRANK B. FOSTER.
